UNITED STATES PATENT OFFICE.

THOMAS J. COO, OF TORONTO, ONTARIO, CANADA, ASSIGNOR TO VICTORY AUTOMOBILE ACCESSORIES LIMITED, OF TORONTO, CANADA, A CORPORATION OF ONTARIO.

DOORLATCH.

Application filed November 13, 1920. Serial No. 423,840.

To all whom it may concern:

Be it known that I, THOMAS J. Coo, a subject of the King of Great Britain, and resident of the city of Toronto, county of York, Province of Ontario, in the Dominion of Canada, have invented certain new and useful Improvements in Door-latches, described in the following specification and illustrated in the accompanying drawings, that form part of the same.

The principal objects of the invention are to eliminate the disagreeable conditions due to ill fitting doors preventing them from rattling, and to devise a very simple form of fastening which may be readily applied to any door.

The principal feature of the invention consists in the novel construction and arrangement of a pivotal member in the keeper of the latch which engages the latch in a wedging contact.

In the drawings, Figure 1 is a perspective view of a portion of a frame of an automobile door showing my improved latch fastener secured thereto.

Figure 2 is a transverse sectional view of my improved fastener showing the edge of the door in a partly closed position and the latch engaging the fastener.

Figure 3 shows the position of the parts when the latch is farther advanced into the keeper.

Figure 4 shows the latch fully advanced into the keeper and wedged tightly into place.

Figure 5 is a perspective detail of a modified form of keeper member.

It is highly desirable that some simple means be provided to overcome the rattling of loose doors of motor cars and carriages and that a device be provided which will be adaptable to any form of door. The device herein shown, as adapted to this purpose, consists of a metal bracket 1 of a substantially wedge shape which forms the keeper.

The bracket member 1 is shown in Figure 1 provided with a pair of lugs 2 through which suitable screws are inserted to fasten the bracket to the door frame, the wedge-shaped portion presenting the bevelled surface 3 in alignment with the path of movement of the latch portion of the door and closing the outward side of the latch recess 4. This side of the bracket facing inwardly

toward the recess 4 is formed with a horizontal slot 5 which cuts into the bevelled face 3 at the outer edge and in this slot is supported a pivotal block 6 mounted upon the pivot pin 7 adjacent to the inward side 60 of the bracket.

The block 6 is peculiarly shaped having a curved spur 8 arranged on the side adjacent to the outer side of the bracket. Extending from the spur is a bevelled surface 65 9, the bevel of which extends away from the pivot of the block and merges into another bevelled surface 10 which also is bevelled away from the axis of rotation of the block and is sloped so that if its inclination were 70 projected back to the spur the inclination would cut the spur back of its point.

The reason for this peculiar arrangement of surfaces in relation to the axis of rotation of the pivotal member of the spur is 75 that which causes the device to be effective.

A latch bolt 11 which is carried in the door 12 is of the ordinary spring variety having a curved inward face and a flat outward face 13.

Referring to Figure 2 it will be seen that the door is just being closed and that the latch bolt has passed over the apex of the bevelled surface 3 of the bracket 1 and has sprung inwardly. The pivotal block 6 is 85 held to the position shown in Figure 2 by means of a flat spring 14, arranged in a recess 15 at the inward side of the block close to the frame and the latch bolt passes the spur 8 and engages the bevelled surface 9 90 and as the door is moved farther in the pressure of the latch spring which is considerably greater than the spring 14 pushing against the bevelled surface 9 oscillates the block 6 on its pivot as illustrated in Figure 95 3, the spur 8 bearing against the face 13 of the latch. This movement continues until the point of the latch bolt slips over the angle of juncture between the faces 9 and 10.

The latch bolt bearing against the point of the spur engages the bevelled face 10 at a very acute angle and a locking effect is produced which holds the latch in place and this bevelled surface takes up any looseness in the fit of the door allowing the latch bolt to come to rest at any desirable point which forms its limit but securely locking the bolt in any position which it assumes and wedging the door tightly into place.

2

It will be seen that the vibration of travel, when the device is used on a motor car, will cause the door to shake and the effect will be to allow the latch to wedge the door tightly 5 against the bevelled surface 10. The spur 8 holds the latch in a proper relative position to the surface 10 but allows the latch to engage the sharper bevel 9 when it is first entering.

10 A device such as described will hold any door tight and prevent it rattling as is readily apparent. It is extremely simple in construction and may be easily and quickly attached to any door frame without interfering 15 with the door lock in any manner or requiring any machine work. The extremely simple construction enables the device to be manufactured at very low cost.

In the modified construction shown in 20 Figure 5 the keeper block 16 is pivoted between the fastening lugs 17 but otherwise is formed the same as the bracket 1 and carries the locking block 6 the same as the other structure. The feature about this modification 25 is that being pivotally supported it can swing outwardly from the door frame to allow of a greater range of adjustment in the event of a bad fitting door.

The latch has been described as applied 30 particularly to doors of motor cars but it may be utilized in connection with windows and other devices where it is desired to hold a movable member from rattling.

What I claim as my invention is:—
35 1. In a door latch, the combination with the latch bolt and keeper, of a member pivotally supported in the keeper formed with a

bevelled surface diverging from the pivot 40 adapted to engage only the flat outer face of the latch and a spur projection at the side nearest the door, said spur engaging the outer face of the latch at a point to the outside of the pivot and holding the bevelled surface of the pivotal member in wedging contact with the latch.

2. In a door latch, the combination with a latch bolt, of a keeper bracket adapted to be fastened to the door frame and having a bevelled surface to engage the latch and a horizontal slot in its inward face, a block 50 pivotally mounted in said slot having a spur projection at one side, and a pair of bevelled faces arranged in obtuse angular relation the one to the other to diverge from the axis of rotation of the block and adapted to wedge 55 against outward face of the latch.

3. In a door latch, the combination with a latch bolt, of a triangular shaped block having fastening lugs adapted to secure the block to the door frame, said block having a 60 transverse slot in its inward face, a pivot pin extending vertically across said transverse slot arranged toward the inward side of the slot, a block pivotally mounted on said pin and having a curved outward side terminating in a spur, the side adjacent to the spur extending therefrom at an angle which diverges from the pivot point of the block, said block having a second angular face merging 65 into the first one at an acute angular inclination in relation to the point of the spur and the point of the block.

THOMAS J. COO.
